UNITED STATES PATENT OFFICE.

WILLIAM E. ABBOTT, OF PASADENA, CALIFORNIA, ASSIGNOR OF ONE-FOURTH TO DENNISON F. REASE, OF SANTA CRUZ, CALIFORNIA, AND ONE-FOURTH TO R. H. CALDWELL AND ONE-EIGHTH TO LOGAN SMITH, BOTH OF SANTA CRUZ, CALIFORNIA.

LIFE PRESERVER.

Application filed August 22, 1923, Serial No. 658,694. Renewed March 17, 1925.

To all whom it may concern:

Be it known that I, WILLIAM E. ABBOTT, a citizen of the United States, residing at Pasadena, in the county of Los Angeles and State of California, have invented certain new and useful Improvements in Life Preservers, of which the following is a specification.

This invention relates to the general class 10 of life preservers of the type worn by individuals, and has particular reference to a buoyant piece of mechanism for individual or personal use either for recreation or pleasure purposes as in bathing or swimming, for use on ship board, or for use in connection with water craft for use in case of accident or the like.

Among the objects of the invention is to improve this class of devices with respect 20 to a number of features among which may be noted the following: Ease and simplicity of application to the person; facility for carrying or storage purposes; maximum reliability for sustaining the wearer with 25 his head or face elevated above the surface of the water irrespective of the position of the other parts of the body; maximum freedom for movement of the individual and especially his arms and legs while in the 30 water; practical immunity from loss of life as a result of puncturing or other damage to the device while in use; ease of adjustability of the device, making it adaptable to persons of different sizes, and other 35 advantages and purposes that will be apparent as this description progresses.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to the accompanying drawings, in which like 45 reference characters designate the same parts in the several views, and in which—

Figure 1 is a front perspective view show-

ing a preferred embodiment of the invention.

50

Fig. 2 is a side view of the same.

Fig. 3 is a rear view.

Fig. 4 is an inside or front elevation of the device detached and indicating slight 55 modifications in detail.

55

Fig. 5 is a sectional detail indicating the manner of sealing the casing ends.

Referring now more specifically to the drawings my improved life preserver is shown herein as comprising two buoyant 60 members 10 each of which consists preferably of a shell or cover of any suitable but preferably flexible waterproof or impervious material such as rubber or rubberized fabric, or the like, and adapted to be either 65 inflatable or otherwise suitably filled with light material for the sake of maximum displacement. In the form in which this invention has been made and practised extensively the members 10 are of flexible rubber 70 tubing with the ends hermetically sealed at 11, a result that may be accomplished in various ways as by the introduction of cement or by vulcanization. Whatever the means employed for rendering the ends of the 75 members 10 hermetically sealed there are provided flat strong reinforced end tabs which are utilized for attachment purposes and to provide means for securing the device not only to the person but with the two 80 members in proper relation to each other.

For pleasure purposes such as for use at a bathing beach or in a swimming pool it may be preferred that the members 10 be 85 of simple rubber tubing or the like and adapted to be inflated with air at the time the device is to be used. Thus the device may be of a collapsible nature for ease and simplicity of transportation or storage and whereby it will occupy very little space 90 when deflated. For inflation each member is provided with a nozzle or nipple 12 which may be located at any convenient place. For this purpose Figs. 1 and 2 indicate the nozzles located at the sides of the person 95 and near the ends of the members 10. In

- Fig. 4, however, the nozzles 12' are indicated as located nearer the central portions 10 and within reach of the person's mouth while the device is being worn so that it is 15 possible under certain conditions for the user of the device to maintain the members suitably inflated while being worn. I wish to emphasize at this time, however, that while for some purposes the members may 20 be filled with air or other suitable buoyant gas, the spirit of the invention contemplates the filling of the casings with any other suitable bulky and buoyant material such as kapok, other vegetable or animal fibrous material, sawdust, cork composition, or the like, but in all cases the casings 10 should be of such a nature as to be preserved 25 water-tight and of sufficient strength for the purpose intended.
- 20 The casings may be described as being of substantially horseshoe shape when inflated or filled and they are designed to be worn by the person with the central or bend portions directly over his shoulders on opposite 25 sides of his neck. The rear portions of the casing are maintained substantially parallel and in close relationship to each other along the wearer's back or close to his backbone, the rear ends being anchored close 30 to each other as by being attached to a waist band or belt 13, and a tie member 14 is looped around the neck or shoulder blade portions of the casings and extends across the back of the wearer's neck. This tie 35 member is in the nature of a strap of any suitable, durable, preferably non-elastic but flexible material looped around the casings sufficiently tightly to make it practically self retained in position while in use and still 40 capable of adjustment longitudinally along the back portions of the casings so as to adapt the device to the individual wearer or wearers of different sizes or builds, said tie member, from its structural nature, affording a convenient and reliable hand grip 45 for a child or other individual whom the wearer of the life preserver may desire to afford support. In all cases practical freedom of the person's head and neck will be 50 assured.
- 55 The front end portions of the casings are secured in any suitable manner to the belt adjacent to the ends thereof so that when the belt is attached as by means of a buckle 15 or its equivalent at the front of his body as usual, the front portions of the casings will be approximately parallel to each other and spaced according to the width of his neck.
- 60 The attachment means between the casing ends 11 and the belt may be as desired and to this end I show rivets 16 or stitching 17. Separable fasteners, especially for the front for maximum adjustment along 65 the belt might be employed but for maxi-

mum reliability I recommend the use of permanent fasteners.

When the casings are made of flexible and elastic rubber the ends 11 before being sealed are preferably provided with pieces of non-elastic material such as fabric 18 so as to give ample strength for the anchorage of the device. The fabric thus inserted becomes thoroughly impregnated with the rubber composition during vulcanization. 75

The application of the device as shown and described may be effected readily by simply passing it over the arms and shoulders like a vest and fastening the buckle or its equivalent in front. Because of the close attachment of the rear portions of the casings to each other all along the line between the waist band and the neck, the loop portions of the casings are retained reliably in place and therefore the only attachment 80 means necessary to be depended upon is the buckle at the front. It will be observed naturally that the position of the life preserver as shown causes no obstruction to the arms or any other part of the wearer's 85 person or body and so he is free to exert every effort necessary to reach the land in safety while the buoyancy of the device will insure that his face at least will be kept above the surface of the water irrespective 90 of the position of all other parts of his body in the water. The device is peculiarly well adapted for the use of bathers and swimmers, especially in enabling one to learn the 95 art of swimming, because of the fact that 100 all the longer lines of the device, that is, those portions along the back and the chest of the wearer, are practically parallel to one another and the line of progress through the water, as distinguished from life buoys 105 or life preservers as usually made, which are bulky in directions transverse to the direction of propulsion. Again, the construction of this improvement with respect to 110 its attachment to the person, adapts it particularly well for the making of a rescue. For example, a swimmer or other person with the device attached as shown may swim or float for a long time and with a child or other person located upon the swimmer's or 115 wearer's back and holding to the tie member 14 as a convenient and reliable hand hold. The buoyancy of the device is ample for sustaining several persons in safe position. Furthermore, the fact that two casings 10 120 are employed adds also to the reliability of the device in practice even though one of them may become punctured or disabled while being inflated with air or gas. 125

I claim:

1. In a life preserver, the combination of a pair of substantially similar buoyant flexible members adapted to be applied and to fit close to the wearer's trunk, said members being of horseshoe shape with the bends over 130

the wearer's shoulders, a waist belt, and flexible means coacting with the ends of the members and serving to seal the same and constitute reinforcing anchorages between the members and the belt.

2. The herein described life preserver comprising a buoyant member consisting of a piece of flexible elastic rubber tubing, the ends of the tubing being hermetically sealed,

a piece of strong nonelastic material being applied within each end of the tubing and vulcanized in such position for a strong anchorage, and means cooperating with said ends of the tubing to secure the device to the person's trunk.

In testimony whereof I affix my signature.

WILLIAM E. ABBOTT.
